ATTORNEY

UNITED STATES PATENT OFFICE.

THOMAS W. EDWARDS, OF PITTSBURGH, PENNSYLVANIA.

PORTABLE DOOR-LATCH.

1,178,504.

Specification of Letters Patent. Patented Apr. 11, 1916.

Application filed September 14, 1915. Serial No. 50,651.

To all whom it may concern:

Be it known that I, THOMAS W. EDWARDS, a citizen of the United States, residing at Pittsburgh, in the county of Allegheny and 5 State of Pennsylvania, have invented certain new and useful Improvements in Portable Door-Latches, of which the following is a specification.

This invention has relation to certain new 10 and useful improvements in portable door latches, and has for its primary object the provision of a portable door latch which will be composed of the minimum number of parts, which may be readily applied and 15 secured to the door frame and which will be highly efficient in use.

The invention has for another object, the provision of a door latch of this character in which the door-engaging member may be 20 hinged to the stationary member adapted to be secured to the edge of the door frame and the door-engaging member constructed in such manner that it will be adapted to engage two faces of the door when pressure is 25 applied to the outer face of the door and thereby prevent the door from being forced open.

The invention has for a further object, the provision of a portable door latch of the 30 above-stated character which will be of such construction and operation that the door engaging member may be readily drawn away from engagement with the door after pressing the latter outwardly when it is desired 35 to permit the door to be opened.

With the above and other objects in view the invention resides in the novel construction, combination and arrangement of parts as hereinafter set forth in the specification, 40 pointed out in the claims and shown in the accompanying drawings, in which—

Figure 1 is a perspective view of my improved form of portable door latch; Fig. 2 is a top plan view thereof with the same 45 in open position; Fig. 3 is a side elevation of the same looking at one side thereof with the parts in open position; Fig. 4 is a fragmentary section through a portion of a door and the adjacent door frame, showing the 50 door secured in closed position by my improved door latch; Fig. 5 is an elevation of the same.

Referring to the drawings in which similar reference characters designate corresponding parts throughout the several views, 1 designates the stationary plate

which is provided at its inner end with the bevel teeth 2 projecting at an angle from the corners of said stationary plate to bite into the side of the door frame 3 opposite the vertical free edge of the door 4 when the stationary plate 1 is applied to the door frame 3. The stationary plate 1 is also provided with a suitable opening 5 through which the securing member 6 may be engaged for securely fastening the stationary plate 1 in position, if desired. The opposite or free end of the stationary plate 1 has extended portions rolled back to form the hinge members 7 to receive a hinge pin 8 which is engaged through the hinge member 9 and formed by extending back a portion of one end of the hinged door engaging member 10. The hinged door-engaging member 10 is bent upon itself about midway its vertical edges, as shown at 11, so that it may readily engage the inner face of the door 4 and the door edge engaging spring finger 12 is struck out of the hinged door engaging member 10 and curved back from about the point 11 and extended in an opposite direction to the outer portion of said hinged door engaging member 10 for engagement with said inner face of the door 4.

When it is desired to use this portable door latch, the stationary plate 1 is properly secured to the edge of the door frame 3 as shown in Fig. 4 of the drawings, and the inner vertical corner of the door 4 engaged between the body of the hinged door engaging member 10 and the finger 12 thereof and the door then swung to closed position, shown in Fig. 4 of the drawings. It will be seen that any pressure against the outer face of the door 4 to open the same will simply force the inner vertical corner of the door 4 tightly into the locking corner 13 of the door engaging member 10 at the point at which the finger 12 connects with the body of said door engaging member 10, thereby causing the finger 12 to bind against the vertical outer or forward edge of the door 4 while the free end of the body of the member 10 bears against the inner face of said door 4, thereby locking the door 4 in closed position, as the member 10 can not under these conditions swing upon the hinge pin 8. When it is desired to release the door 4 to open the same, however, the door 4 is first pressed outwardly, forcing the free end of the finger 12 into the tongue receiving recess 14 formed by striking out and

bending back the portion 15 of the body of the stationary plate 1. This will permit the inner vertical corner of the door 4 to pass over the finger 12 and beyond the free end 5 thereof. The operator's finger or a tool may then be engaged with the free end of the jaw engaging member 10 to swing the same upon the hinge pin 8 to open position, permitting the door 4 to freely swing to open 10 position. The stationary plate 1 may then be removed from the door frame 3 and the device folded into compact form until again required for use.

From the foregoing, it will be readily apparent that this form of portable door latch 15 may be readily carried in the pocket or a suitcase and applied to any door as desired, it being especially desirable for the purpose of locking the doors in rooms of hotels and 20 the like when traveling.

While the preferred embodiments of the invention have been clearly shown and described, it will be understood that minor changes in details of construction, and arrangement of parts may be resorted to 25 within the scope of the appended claims without departing from the spirit of the invention or sacrificing any of the advantages of the same.

30 What is claimed is:

1. A portable door latch comprising a stationary plate, means for securing said sta-

tionary plate to a door frame and preventing turning of said stationary plate, and a forked door engaging member carried by 35 said stationary plate to lock a curved door in closed position within said door frame.

2. A portable door latch comprising a stationary plate adapted to be secured to a door frame, a door engaging member hinged 40 to said stationary plate to lock a door in closed position within said door frame, said door engaging member being adapted for engagement with one face of said door, and a door engaging finger carried by said door 45 engaging member for engagement with a second face of said door at right angles to the first mentioned face thereof.

3. A portable door latch comprising a stationary plate having a door jamb-engaging finger struck out of the same near its outer end, a door-engaging plate hinged to the outer end of said stationary plate, and a centrally curved door-engaging finger struck out of said door-engaging plate and 50 adapted at times to engage with the first-mentioned finger.

In testimony whereof I affix my signature in presence of two witnesses.

THOMAS W. EDWARDS.
